United States Patent Office

Des. 205,963
Patented Oct. 11, 1966

205,963

ELECTRIC ORGAN

William J. Kreizel, Hewlett Harbor, N.Y., assignor to
Emenee Industries, Inc., Flushing, N.Y., a corporation
of New York

Filed Apr. 25, 1966, Ser. No. 2,011

Term of patent 14 years

(Cl. D56—2)

FIG. 1

FIG. 2

FIG. 3

FIG. 4

FIG. 5

FIG. 1 is a perspective view of an electric organ showing my new design;

FIG. 2 is a top plan view thereof;

FIG. 3 is a front elevational view thereof;

FIG. 4 is a rear elevational view thereof, and

FIG. 5 is an end elevational view thereof.

I claim:

The ornamental design for an electric organ, substantially as shown.
